2,483,338

CHAIN-TYPE CUTTER FOR DEBARKING MACHINES

Melvin Douglas, Chicago, Ill., assignor to Harry A. Lowther Co., Chicago, Ill., a firm

Application June 2, 1947, Serial No. 751,715

2 Claims. (Cl. 144—208)

1

My invention relates to machines for stripping the bark from trees. Such machines as have come to my attention either require too long to accomplish the operation or cause the surface underlying the bark to become marred or damaged during the removal of the bark. It is therefore one object of the present invention to provide a debarking machine unit which has a shearing or drawing action, whereby to strip the bark without causing injury to the surface underneath.

A further object is to provide a unit of the above character which works with a diagonal action, so that the bark stripping or removing force is exerted both in a forward and lateral direction to facilitate the easy removal of the bark.

Another object is to design the unit in a manner to operate astride the tree over a path of maximum width, whereby to de-bark a log by turning it only three or four times during debarking operations.

A still further object is to provide means for adjusting the unit to trees of different diameters with a view to securing the most efficient application of the de-barking elements.

An additional object is to include means in the novel unit to render it slightly yieldable and make the operation of the de-barking elements less severe.

An important object is to design the novel unit along lines of ruggedness and simplicity.

With the above objects in view, and any others which may suggest themselves from the description to follow, a better understanding of the invention may be had by reference to the accompanying drawings, in which—

Fig. 1 is a plan view of the machine, showing its application;

Fig. 2 is an enlarged plan view of the de-barking unit;

Fig. 3 is an axial section of the same;

Fig. 4 is a diagrammatic plan view, showing the de-barking operation in progress;

Fig. 5 is a cross-sectional diagrammatic view showing the de-barking unit set over a log of small diameter;

Fig. 6 is a side view of a portion of Fig. 5;

Figs. 7 and 8 are views similar to 5 and 6 in respect to a log of larger diameter; and

Fig. 9 is a diagrammatic view showing operational phases at different adjustments of the debarking unit.

In accordance with the foregoing specific reference to the drawings indicates a power vehicle at 15 which is designed to carry the de-barking unit. Thus, the vehicle frame is extended with

2

a bar 18 in a forward direction, the bar carrying a transverse bearing 17 at its forward end. The bearing journals a shaft 18, and a belt drive 19 extends from the power element of the vehicle to drive the shaft 18. The latter is extended to one side of the vehicle, in order that it may carry the de-barking unit clear thereof; and Fig. 1 shows that the log to be de-barked is in a position alongside the vehicle, and that the de-barking unit is designed to travel over the log from end to end.

The de-barking unit is in the form of a spool, and is partly carried on a hub 25 rigidly attached to the shaft 18 by a cross pin 26. The outer portion of the unit is in the form of a pair of longitudinally-spaced circular discs 28 and 29. The disc 28 is carried by a central sleeve 30, the latter being slidably and rotatably mounted on the hub 25. The disc 29 is spaced outwardly from the hub 25. The latter receives a washer 31 at its outer end; and a compression spring 32 surrounds the shaft 18 between the washer 31 and disc 29. The latter has a hub 35 which is keyed on the corresponding end of the shaft 18 as indicated at 36; and a small disc 37 is placed against the end of the shaft 18 as a retainer for the key 36, the disc 37 being secured to the shaft by a central screw 38.

The discs 28 and 29 are fitted with a circular series of U-bolts 40 which protrude in outward directions to receive securing nuts 41. The U-bolts are designed to secure a series of chains 42 spanning the discs 28 and 29. However, Fig. 2 indicates that the chains are diagonally directed from one disc toward the other; and the tension of the spring 32 is such that the normal condition of the chains is fairly tense.

When the machine is set with the de-barking unit over one end of a tree log, and the unit is put in rapid rotation, the progress of the vehicle toward the other end of the tree is designed to remove the bark over a portion of considerable width, such as is indicated at 45 in Fig. 4. The mean line of contact of the chains 42 which engage the log is represented by the line 46 in the same figure. Thus, the travel of the chains in the contact zone is in the general direction of the arrow 47, but the oblique position of the working chains not only acts to dislodge or strip the bark from the log, but has a shearing action to remove the severity or abruptness of the stripping action. In other words, the action of the engaging chains is on a bias. Further, Fig. 5 shows that the chains, represented by the lines A—A and B—B, 50 combine to close or wrap themselves over the

upper portion of the log to a considerable extent, securing a wide stripping area.

The discs 28 and 29 are adjustable toward each other for the purpose of adapting the barking unit to logs of different diameters. Thus, Figs. 5 and 6 show the discs placed closely to adapt the unit to a log of relatively small diameter, while Figs. 7 and 8 show the discs more widely spaced to accommodate a log of larger diameter. In both cases, the purpose is to secure the wrapping of the chains over a portion of such width as will combine operative efficiency with maximum surface coverage, so that the log would only have to be turned three or four times between stripping operations to become fully de-barked. Fig. 9 indicates the profile of working chains at different spacings of the discs 28 and 29.

While any suitable method may be used for adjusting the spacing of the discs 28 and 29, the positive construction illustrated is preferable. Thus, the hub 25 is made with three spiral series of tapped cavities 50, and the sleeve 30 contains a circularly spaced series of three set screws 51. Thus, the disc 28 may be advanced or retracted along the hub 25 with a rotary motion to bring the set screws 51 in line with the corresponding series of cavities 50, so that the securing of the set screws in this manner firmly tightens the sleeve 30 on the hub 25, placing the disc 28 at the desired spacing from the disc 29.

It will now be evident that the novel de-barking unit is of a compact and self-contained nature, so that it may be mounted on any traveling carrier which provides a suitable bearing for the driven shaft 18. The assembly of the central parts of the unit is sturdy and simple; and the cluster of chains is along the periphery of the unit and therefore accessible for attention or replacement. The unit may be set to any width according to the diameter of logs in a given job, and the work negotiated and carried out with efficiency throughout the job, whereby to strip the bark neatly and expeditiously. Further, it is an easy matter to adjust the discs of the unit for a job where the diameter of the logs is different. Finally, the novel unit is made of few and simple parts, whereby to be economically produced.

While I have described the invention along specific lines, various minor changes or refinements may be made therein without departing from its principle, and I reserve the right to employ all such changes and refinements as may come within the scope of the appended claims.

I claim:

1. A log debarking machine comprising a carrier adapted to travel in a course parallel to the log and having a power drive, a transverse shaft driven by the latter, and a debarking unit operated by the shaft and engageable with the sur-

face of the log during the travel of the carrier, said unit comprising a pair of discs carried by the shaft in spaced relation, oppositely positioned attaching elements carried by the outer peripheral portions of the discs at equal radial distances from the shaft, a plurality of chains spanning the discs, each chain being secured endwise to a non-opposite pair of said attaching elements, whereby the chains are positioned diagonally between said discs and in spaced uniform relation about said shaft, one of said discs being mounted to slide along the shaft toward the other disc, and yieldable means opposing movement of the slideable disc toward the other disc to normally maintain said chains in substantially taut condition.

2. A log debarking machine comprising a carrier adapted to travel in a course parallel to the log and having a power drive, a transverse shaft driven by the latter, and a debarking unit operated by the shaft and engageable with the surface of the log during the travel of the carrier, said unit comprising a pair of discs disposed spacedly along the shaft, one disc being made fast to the latter, oppositely positioned attaching elements carried by the outer peripheral portions of the discs at equal radial distances from the shaft, a plurality of chains spanning the discs, each chain being secured endwise to a non-opposite pair of said attaching elements, whereby the chains are positioned diagonally between said discs and in spaced uniform relation about said shaft, a sleeve carrying the other disc and slideable on the shaft, the latter having a plurality of tapped cavities arranged in a plurality of spiral series, each cavity of one series being circumferentially aligned with a corresponding cavity in each of the other series, and a plurality of bolts carried by the sleeve, there being one bolt for each spiral series, whereby the spacing of said discs can be varied by first removing the bolts from one set of circumferentially aligned cavities, then sliding and rotating the sleeve and securing the bolts in a different set of aligned cavities.

MELVIN DOUGLAS.
